US00D635420S

(12) **United States Design Patent**
Fischer

(10) **Patent No.:** **US D635,420 S**
(45) **Date of Patent:** **** Apr. 5, 2011**

(54) **SKATEBOARD MULTI-TOOL COMBINATION
WRENCH**

4,774,736 A * 10/1988 Brawner et al. 7/138
6,279,434 B1 * 8/2001 Brown 81/437
7,530,295 B2 * 5/2009 Jones et al. 81/124.4

(76) Inventor: **Brett William Fischer**, Lee's Summit,
MO (US)

* cited by examiner

(**) Term: **14 Years**

Primary Examiner — Raphael Barkai
Assistant Examiner — Randall Gholson

(21) Appl. No.: **29/372,662**

CLAIM

(22) Filed: **Dec. 22, 2010**

The ornamental design for a skateboard multi-tool combination wrench.

(51) **LOC (9) Cl.** **08-05**

DESCRIPTION

(52) **U.S. Cl.** **D8/28**

(58) **Field of Classification Search** D8/14,
D8/17, 21–29, 354, 107; 81/60, 177.1, 177.85,
81/121.1, 124.3, 165–170, 110.1, 176.2,
81/124.6, 176.1, 176.15, 177.2, 186, 437–439,
81/489, 490, 177.4; 16/110.1; D15/144.1,
D15/143; 219/75, 227, 229, 121.16, 121.18;
7/138, 165, 139

See application file for complete search history.
